[57] CLAIM

The ornamental design for a telecommunications system console or similar article, substantially as shown and described.

DESCRIPTION

FIG. 1 is a perspective view of a telecommunications system console or similar article embodying our new design, the console having a door that is shown in its open position;

FIG. 2 is a top plan view with the door in its closed position, the broken line showing here is for illustrative purposes only and form no part of the claimed design;

FIG. 3 is a right side view, the left side being a mirror image of the side shown; and

FIG. 4 is a front elevational view, the rear being a mirror image of the front side shown.

FIG. 2

FIG. 3

FIG. 4
